WEED-CUTTING TOOL

Andrew C. Popivalo, 2028 Webster St., Sanger, Calif.

Filed Mar. 2, 1959, Ser. No. 54,796

Term of patent 14 years

(Cl. D35—2)

Fig. 1 is a front perspective left-side view taken from the right side of the weed-cutting tool embodying my new design, the rear not shown being substantially plain,

Fig. 2 is an enlarged fragmentary perspective right-side view taken from the left side thereof showing the blade portion,

Fig. 3 is a left right-side elevational view of Fig. 2 in position for use, but showing the complete ferrule.

The characteristic features of my design reside in the blade portions of the weed-cutting tool as shown.

I claim:
The ornamental design for a tweed-cutting tool, substantially shown and described.
